UNITED STATES PATENT OFFICE.

JOHN H. SHAW, OF NEW HAVEN, CONNECTICUT.

BRAKE FOR CAR-WHEELS.

No. 864,268.

Specification of Letters Patent.

Patented Aug. 27, 1907.

Application filed December 14, 1906. Serial No. 347,835.

To all whom it may concern:

Be it known that I, JOHN H. SHAW, a citizen of the United States, residing in the city and county of New Haven, in the State of Connecticut, have invented 5 new and useful Improvements in Brakes for Car-Wheels, of which the following, in connection with the drawings, is a specification.

My invention which relates to that class of brakes comprising a holder and a detachable or renewable 10 brake shoe has for its object the production of a shoe which will remain operative in case it is broken; and has attaching devices which will give the shoe or the parts of the shoe, if broken, a rocking bearing in the holder with reference to the braking surface of the 15 wheel, and prevent lateral movement of the shoe or parts of the shoe in the holder, and which will accomplish these results by a simple and cheap construction of the parts, and to these and other ends 20 consists in the various improvements and combinations of parts set forth and claimed hereinafter.

In the drawings, Figure 1 represents a perspective view of the shoe alone, Fig. 2, a similar view of the holder alone, Fig. 3, a similar view of the shoe and holder together, Fig. 4, another view, in perspective, 25 of the holder, Fig. 5, a cross section of the holder and shoe on line 5—5 of Fig. 3, Fig. 6, a perspective view of the retaining strap, and Fig. 7, a perspective view of a portion of the shoe.

In all figures, similar letters of reference indicate 30 like parts.

In the drawings, the parts designated by the letter A represent the body of the holder, of the usual curved form, and B the eye for attachment to the brake bottom.

35 C designates a plurality of parti cylindrical recesses formed in and extending across the front face of the holder, their openings into said face being narrower than the width of said recesses inside of the openings. A slot D extends from end to end of the holder, the 40 longitudinal plane of said slot passing through said recesses C.

E designates the body of the brake shoe, and F, a plurality of transverse projections cast upon and extending across the back of the brake shoe corresponding 45 in position and in cross section to the position and shape of the recesses C in the holder A. Slots G are cast in the projections F, so that when the parts are assembled these slots will come into the longitudinal plane of the slot D in the holder.

50 A metallic strap H shaped to conform to the curvature of the brake shoe and holder is provided, so that when the same are assembled it will pass through the slot D in the holder, and through the slots G in the projections F. One end I of the strap H is turned to 55 form a stop, and the other end is provided with a hole K for a cotter pin (not shown).

The brake shoe and holder are assembled by sliding the projections F laterally into the recesses C, said projections and recesses dovetailing loosely into each other to lock the shoe and holder together. The strap 60 H is then passed through the slot in the holder A, and through the slots in the projections of the brake shoe, and thus prevents lateral movement of the shoe in the holder. The strap is secured in place by a cotter pin. 65

The projections F are preferably rounded on the back, as shown, so that when the parts are assembled, the rounded projections on the back of the brake shoe bear upon the body of the holder in the bottom of the recesses, and said projections fit loosely in said recesses, so as to permit a rocking motion of the shoe on one or another of the projections F, enabling the brake shoe to accommodate itself to the surface of the wheel. 70

The principal object of providing a plurality of transverse recesses in the holder, and transverse projections in the shoe is to provide for the continued efficiency of the brake after the shoe is broken, which must ultimately happen as the shoe wears thin or is subjected to a breaking strain. 75

Nicks L are provided between each of the projections F on the shoe, so that shoes so constructed will break transversely on these lines between the projections F, and each portion of the shoe then remains seated on its own rocking bearing. A portion of a shoe 80 so broken is shown in Fig. 7. The efficiency of the shoe remains unimpaired, and further breaking is practically eliminated, because each portion of the shoe is then at liberty to accommodate itself independently to the surface of the car wheel. Lateral 90 displacement of the brake shoe, or of the parts of the shoe, when broken, with respect to the holder is prevented by the strap H passing through the slots D and G. As the efficiency of the brake shoe when so constructed and combined with the holder is not impaired by any ordinary fracture, it may be used until 95 worn down very thin, and may then be easily replaced or renewed.

The construction of the parts is simple, and the shoe and holder may be formed by casting without 100 any necessity for finishing or fitting, because the construction is such that looseness of fit is consistent with the shoe being firmly retained in its operative position.

Having now described my invention, what I claim and desire to secure by Letters Patent, is:— 105

1. In a car brake, the combination with a holder, provided with a plurality of transverse recesses; of a shoe provided with a plurality of corresponding transverse projections on the back thereof adapted to fit loosely in said recesses in the holder and bearing against the bottom of said recesses; and means for retaining said projections in said recesses, substantially as and for the purposes described. 110

2. In a car brake, the combination with a holder, provided with a plurality of transverse recesses; of a shoe provided with a plurality of corresponding transverse projections on the back thereof adapted to fit in said recesses in the holder, said shoe being adapted when broken to form a series of shoes, each having one of said projections, substantially as and for the purposes described.
3. In a car brake, the combination with a holder, provided with a plurality of transverse recesses; of a shoe provided with a plurality of corresponding transverse projections on the back thereof adapted to fit in said recesses

in the holder; and a pin adapted to pass through said recesses and engage said projections to prevent the independent lateral displacement of said shoe or holder, substantially as and for the purposes described.

15

In witness whereof, I have hereunto set my hand on the 10th day of December, 1906.

JOHN H. SHAW.
